UNITED STATES PATENT OFFICE

SPENCER M. PETERS AND ARTHUR B. ROCHESTER, OF SPRINGFIELD, ILLINOIS; SAID
ROCHESTER ASSIGNOR TO SAID PETERS

ADJUSTABLE AUTOMATIC FOLDING PLATFORM FOR STEP-LADDERS

Application filed March 27, 1929. Serial No. 350,836.

Our invention relates to platforms for step-ladders and the like and more particularly relates to platforms adapted to be automatically folded as a step-ladder is folded to a closed position without the necessity of controlling the movement of the platform by any special hand control when the ladder is being folded.

Another object of our invention is to provide as a platform for stepladders a convenient, economical, practical and durable step-ladder platform adapted to meet all the known purposes of a step-ladder platform which may be operatively connected intermediate the top and bottom of the ladder.

A further purpose of our invention is to provide in connection with a step-ladder and an intermediate platform a detachable step adapted to be quickly and conveniently attached and detached and when in normal use inserted on the stiles between the platform and the top of the ladder where it may be desired to climb to the top of the ladder instead of standing on the platform.

A further object of our invention is to provide an automatic adjustable step-ladder platform having adjustment means adapted to keep the platform when in normal use in an approximate horizontal position regardless of the relative pivotal adjustment between the ladder stiles and the ladder supporting legs within predetermined limits of pivotal adjustment between them.

We attain the objects of our invention in the device described in the annexed specification, recited in the claim, and illustrated in the accompanying drawings in which like reference numerals indicate like parts in the several figures.

Referring to the figures:

Fig. 1 is a perspective of a step-ladder showing our step-ladder platform as when in normal use.

Fig. 2 is a top or plan view of a step-ladder with a cross section taken from *a*—*b* on Fig. 4 in order to the more completely disclose the mechanical structure of our step-ladder platform.

Fig. 3 is a perspective of a detachable lad-

der-step adapted to be removed when it is desired to stand on our ladder platform.

Fig. 4 is a vertical half section of a step ladder shown as when in an assembled position and opened in a manner shown in Fig. 1.

Fig. 5 is a vertical cross section of a step ladder shown in folded position of the folding parts including the folded position of the ladder platform.

Referring now in detail to the construction of our step-ladder platform and the preferred manner of operating the same we provide a platform member —1— hingedly connected to the ladder supporting leg structure by hinges —2— and —3— while ladder platform —1— has a pivotal controlling **U** bar —4— extending through the body of the platform intermediate the pivoted and free end position and connected to the platform —1— thru angle bars —5— and —6— and having the lower ends —7— and —8— of the **U** bar normally fitting into adjustment holes —9— and —10— in stiles —11— and —12— of the step ladder to which the platform is operatively connected. Our platform —1— is hingedly connected to its supporting bracket —13— secured to one of the brace members —14— of ladder legs —15— and —16— to which ladder brace member —17— is also attached.

When our ladder is spread open for use our platform —1— rests with its free end on a rung —18— secured to stiles —11— and —12— on the approximate level with the supporting bracket —13— of the platform —1—. Steps —19— are shown as flat steps but may be any suitable design of step-ladder step, this detail being unimportant to the essential operation of our invention.

It will be noted in Fig. 4 that the ladder is shown in solid lines with the supporting legs fully extended and in dotted lines the ladder is shown partially folded with the platform of our invention as a result partially lifted to a folded position.

When it is desired to actually use the ladder with the supporting legs and stiles pivotally moved closer together, then in order to keep platform —1— in horizontal position while being thus used, ends —7— and —8—

of U bar —4— may be inserted into a pair of the lower holes —9— and —10— in stiles —11— and —12—; an adjustment which will merely extend platform —1— further out over rung —18— while it still retains its horizontal position.

When the step-ladder is in normal use it may be desirable to use the top shelf —20—.

It will be seen that as long as the platform —1— is in use then the extra step —21— may not be needed, especially when the user desires to stand on the platform; but when it is desired to climb to the top of the ladder then detachable step —21— is secured in position for use, in which tongue —22— of the step engages bracket —23— on stile —11— while bolts —24— and —25— engage holes —26— and —27— respectively in stile —12—.

When folding the ladder so that the leg members —15— and —16— thereof pivotally move toward stiles —11— and —12—, U bar —4— automatically pushes up on platform —1— and keeps pushing it up until platform —1— comes into alignment with the ladder supporting legs —15— and —16— as shown in Fig. 5.

Having thus described the nature of our step ladder platform and its preferred manner of operation what we claim is:

In a ladder construction of the character described the combination with a pivoted ladder member and supporting leg members pivotally connected at the top and a series of steps on said ladder member terminating short of the pivot ends; a bracket on said leg members, an adjustable automatic folding platform pivotally mounted on said bracket on said leg members and extending between the stiles of said ladder member folding up therewith when not in use and resting at the free end thereof in a horizontal plane on one of said steps when in operative position; a U bar extending pivotally through said platform between its pivoted end and free end and pivotally and detachably engaging said stiles of the ladder member; said last named stiles having aligned adjustment holes adapted to provide means for adjusting the pivotal relation of said ladder member and leg members when in normal use while still holding said platform in a horizontal position.

In witness whereof, we hereunto set our hands this 25th day of March, 1929.

SPENCER M. PETERS.
ARTHUR B. ROCHESTER.
